UNITED STATES PATENT OFFICE

101,411

DESIGN FOR A LAMP

Stephen Zidek, Chicago, Ill.

Application July 17, 1936, Serial No. 63,912

Term of patent 3½ years

To all whom it may concern:

Be it known that I, Stephen Zidek, a citizen of the United States, residing at Chicago, in the county of Cook and State of Illinois, have invented a new, original, and ornamental Design for a Lamp, of which the following is a specification, reference being had to the accompanying drawing, forming part thereof, in which:

Fig. 1 is a perspective view of a lamp showing my new design; and

Fig. 2 is a front elevation thereof.

The dominant feature of my design resides in the shade holding bracket.

I claim:

The ornamental design for a lamp, as shown and described.

STEPHEN ZIDEK.
